UNITED STATES PATENT OFFICE
2,455,106
TOE CREEPING MACHINE
Robert W. Wirtz, Peoria, Ill.
Application November 12, 1947, Serial No. 785,475
15 Claims. (Cl. 12—7)

1 This invention relates to shoe making and has special reference to a ballet shoe toe creaser.

In the manufacture of ballet shoes the most difficult operation is the formation, underneath the toe portion of the shoe, of long, straight, even wrinkles running longitudinally of the shoe and providing alternate ribs and grooves. This operation has heretofore been considered a manual operation and has not only required the services of a highly trained operator but has also required much time.

The principal object of this invention is to provide a novel apparatus whereby creasing for the production of such wrinkles may be quickly and correctly accomplished by a person with practically no skill as well as is done by the most skilled operator.

Another important object of the invention is to provide a novel mechanism whereby the creasing is done successively from the center of the shoe outwardly.

A further object of the invention is to provide means of novel character to support the shoe and secure even spacing of the creases.

A still further object of the invention is to provide a novel arrangement of the mechanism whereby only a small width of the shoe will be creased at a time so as to avoid the undue strain on the leather which would occur if the entire surface was attempted to be creased at one time.

Yet another object of the invention is to provide means whereby the crease forming means may be releasably locked in desired crease forming position.

With the above and other objects in view, the invention consists in general of certain novel details of construction and combinations of parts hereinafter fully described, illustrated in the accompanying drawings and particularly claimed.

In the accompanying drawings like characters of reference indicate like parts in the several views, and—

Figure 1 is a perspective view of a general assembly of the operative parts of the machine and showing a portion of a ballet shoe in position thereon.

Figure 2 is a partial section on the line 2—2 of Figure 1.

Figure 3 is a detail section on the line 3—3 of Figure 1 showing the disclosed parts in one position.

Figure 4 is a detail section on said line 3—3 of Figure 1 with the parts in another position.

Figure 5 is a section on the line 5—5 of Figure 1.

2 It is to be noted that there is here shown only the working parts of the machine but it is to be understood that these parts are to be mounted on a frame, bench or other suitable means to hold the parts in proper operative relationship.

The apparatus itself includes a casing 10 having side walls 11 wherein is journaled a shaft 12 provided on one end with a crank 13. At the central portion of the shaft 12 there is fixed a pair of laterally spaced cam arms 14 and spaced successively outside of each of these are paired cam arms 15, 16 and 17. These cam arms are so spaced around the shaft that they may be brought in pairs into the vertical position shown by the cam arms 14 in Figure 2. Alternating on the shaft 12 with these cam arms are disks 18. Behind the disks 18 is a shaft 19 which has its ends fixed in the casing sides 11. Rockingly mounted on the shaft 19 is a series of levers 20 each having a forward end extending below and engageable by a respective cam arm. These levers are received in the spaces between adjacent disks 18. These levers also have rear arms 21, which are connected individually by springs 23 to an anchor block 22. From the drawings it will be plain that rotation of the shaft 12 by the crank 13 will effect successive depression of the forward ends of the levers 20 and that after each cam passes the vertical position shown in Figure 2 the forward ends of the lever controlled by that cam will rise under the influence of a spring 23, these preferably being coiled tension springs.

There is also provided a finger plate which consists of parallel fingers 24 mounted on a pair of rods 25 and held in spaced relation by spacers 26, the spacing of the fingers being such as to permit the entry between adjacent fingers of one of the levers and two thicknesses of leather as clearly shown in Figures 3 and 4.

In order to hold the forward ends of the levers 20 in selectively depressed adjustment there is provided a vertically fixed ratchet bar 27 having teeth 28 equal in number to the number of pairs of cam arms and, therefore, equal in number to the number of pairs of levers 20. A pedal 29 is supported at one end by a fulcrum 30 and is connected by a link or tie 31 with the crank 13. The free end of this pedal moves beside the ratchet bar and has enough lateral play to be engaged beneath and freed from any tooth 28. By this means any pair of levers 20 may have their forward ends latched down.

In connection with the above described mechanism there is provided the usual last 32, and in operation the last is positioned in front of the

levers, with an insole 33 placed thereon. The shoe upper is then put in position on the last and the rear sides and heel portions brought over and pasted down on the insole. Paste is then applied to the forward portion of the insole. In the manufacture of this type of shoe a wide sole lapping portion is provided at the front of the shoe so that it may be brought back and form a loose portion 35. Before this portion has been brought back the finger plate is positioned on the pasted insole in such manner that the levers will properly engage between the fingers. Now the folding over of the toe leather is accomplished and the finger plate will lie beneath this loose leather. The crank is now operated whereupon the middle pair of levers will come down as in Figure 3. Further movement of the crank will bring down the next pair of levers. Also in Figure 4 the middle pair of fingers are shown as fully depressed which causes the toe leather to engage on the pasted portion of the insole. When any pair of levers is in such engagement, the pedal may be latched and thus hold the engagement until the paste has sufficiently set. When all the loose toe leather has been gathered in this manner the finger plate is withdrawn, a sole (not shown) is put in place to cover the ends of the creases and is stitched in place, completing this part of the shoe.

What is claimed is:

1. In a ballet shoe toe creaser adapted to co-operate with a finger plate having spaced fingers positioned on a shoe, levers movable into and out of the spaces between said fingers, a lever operating device for so moving said levers, and a latching device co-operating with the lever operating device to restrain the levers selectively from moving from between said fingers.

2. In a ballet shoe toe creaser adapted to co-operate with a finger plate having spaced fingers positioned on a shoe, levers movable into and out of the spaces between said fingers, and a lever operating device for so moving said levers, said operating device being arranged to move said levers in successive pairs.

3. In a ballet shoe toe creaser adapted to co-operate with a finger plate having spaced fingers positioned on a shoe, levers movable into and out of the spaces between said fingers, a lever operating device for so moving said levers, said operating device being arranged to move said levers in successive pairs, and a latching device co-operating with the lever operating device to restrain the levers selectively from moving from between said fingers.

4. In a ballet shoe toe creaser adapted to co-operate with a finger plate having spaced fingers positioned on a shoe, spaced levers movable into and out of the spaces between said fingers, a shaft, spaced cams on said shaft engaging said levers for moving said levers into the spaces between said fingers, and springs engaged with said levers and acting in opposition to said cams.

5. In a ballet shoe toe creaser adapted to co-operate with a finger plate having spaced fingers positioned on a shoe, spaced levers movable into and out of the spaces between said fingers, a shaft, spaced cams on said shaft engaging said levers for moving said levers into the spaces between said fingers, springs engaged with said levers and acting in opposition to said cams, and latch means restraining movement of said cams into position to allow selective levers to move from between selective fingers of said finger plate.

6. In a ballet shoe toe creaser adapted to co-operate with a finger plate having spaced fingers

positioned on a shoe, spaced levers movable into and out of the spaces between said fingers, a shaft, spaced cams on said shaft engaging said levers for moving said levers into the spaces between said fingers, springs engaged with said levers and acting in opposition to said cams, and guide plates on said shaft alternating with said cams.

7. In a ballet shoe toe creaser adapted to co-operate with a finger plate having spaced fingers positioned on a shoe, spaced levers movable into and out of the spaces between said fingers, a shaft, spaced cams on said shaft engaging said levers for moving said levers into the spaces between said fingers, springs engaged with said levers and acting in opposition to said cams, latch means restraining movement of said cams into position to allow selective levers to move from between selective fingers of said finger plate, and guide plates on said shaft alternating with said cams.

8. In a ballet shoe toe creaser adapted to co-operate with a finger plate having spaced fingers positioned on a shoe, spaced levers movable into and out of the spaces between said fingers, a shaft, spaced cams on said shaft engaging said levers for moving said levers into the spaces between said fingers, said cams being spaced around said shaft in pairs and successively engaging and operating pairs of the levers, and springs engaged with said levers and acting in opposition to said cams.

9. In a ballet shoe toe creaser adapted to co-operate with a finger plate having spaced fingers positioned on a shoe, spaced levers movable into and out of the spaces between said fingers, a shaft, spaced cams on said shaft engaging said levers for moving said levers into the spaces between said fingers, said cams being spaced around said shaft in pairs and successively engaging and operating pairs of the levers, springs engaged with said levers and acting in opposition to said cams, and latch means restraining movement of said cams into position to allow selective levers to move from between selective fingers of said finger plate.

10. In a ballet shoe toe creaser adapted to co-operate with a finger plate having spaced fingers positioned on a shoe, spaced levers movable into and out of the spaces between said fingers, a shaft, spaced cams on said shaft engaging said levers for moving said levers into the spaces between said fingers, said cams being spaced around said shaft in pairs and successively engaging and operating pairs of the levers, springs engaged with said levers and acting in opposition to said cams, and guide plates on said shaft alternating with said cams.

11. In a ballet shoe toe creaser adapted to co-operate with a finger plate having spaced fingers positioned on a shoe, spaced levers movable into and out of the spaces between said fingers, a shaft, spaced cams on said shaft engaging said levers for moving said levers into the spaces between said fingers, said cams being spaced around said shaft in pairs and successively engaging and operating pairs of the levers, springs engaged with said levers and acting in opposition to said cams, guide plates on said shaft alternating with said cams, and latch means restraining movement of said cams into position to allow selective levers to move from between selective fingers of said finger plate.

12. In a ballet shoe toe creaser adapted to co-operate with a finger plate having spaced fingers positioned on a shoe, spaced levers movable into and out of the spaces between said fingers, a shaft, spaced cams on said shaft engaging said levers for

moving said levers into the spaces between said fingers, springs engaged with said levers and acting in opposition to said cams, a crank on said shaft, a pedal lever having operative connection with said crank, and a latch bar wherewith said pedal lever engages.

13. In a ballet shoe toe creaser adapted to co-operate with a finger plate having spaced fingers positioned on a shoe, spaced levers movable into and out of the spaces between said fingers, a shaft, 10 spaced cams on said shaft engaging said levers for moving said levers into the spaces between said fingers, springs engaged with said levers and acting in opposition to said cams, guide plates on said shaft alternating with said cams, a crank on said shaft, a pedal lever having operative connection with said crank, and a latch bar wherewith said pedal lever engages.

14. In a ballet shoe toe creaser adapted to co-operate with a finger plate having spaced fingers positioned on a shoe, spaced levers movable into and out of the spaces between said fingers, a shaft, 20 spaced cams on said shaft engaging said levers for moving said levers into the spaces between said fingers, said cams being spaced around said shaft in pairs and successively engaging and operating pairs of the levers, springs engaged with said

levers and acting in opposition to said cams, a crank on said shaft, a pedal lever having operative connection with said crank, and a latch bar wherewith said pedal lever engages.

15. In a ballet shoe toe creaser adapted to co-operate with a finger plate having spaced fingers positioned on a shoe, spaced levers movable into and out of the spaces between said fingers, a shaft, 10 spaced cams on said shaft engaging said levers for moving said levers into the spaces between said fingers, said cams being spaced around said shaft in pairs and successively engaging and operating pairs of the levers, springs engaged with said levers and acting in opposition to said cams, guide plates on said shaft alternating with said cams, a crank on said shaft, a pedal lever having operative connection with said crank, and a latch bar wherewith said pedal lever engages.
